K. F. ELLEGARD

INTERNAL COMBUSTION ENGINE

Filed July 16, 1920

Fig. 1.

UNITED STATES PATENT OFFICE.

KAY FREDRICK ELLEGARD, OF HARTFORD, CONNECTICUT.

INTERNAL-COMBUSTION ENGINE.

Application filed July 16, 1920. Serial No. 396,773.

To all whom it may concern:

Be it known that I, KAY FREDRICK ELLEGARD, a citizen of the United States, and a resident of Hartford, in the county of Hartford and State of Connecticut, have invented a new and Improved Internal-Combustion Engine, of which the following is a specification.

My invention relates to that class of engines in which the power is derived by the ignition and explosion of fuel within the cylinder, and an object of my invention, among others, is to provide an engine of this type, of simple construction, and that shall be particularly efficient in operation.

One form of engine embodying my invention and in the construction and use of which the objects herein set out, as well as others, may be attained, is illustrated in the accompanying drawings, in which—

Figure 1 is a view partially in side elevation and partially in central vertical section through the upper part of an engine embodying my invention.

Figure 2 is a view in cross section on plane denoted by the full line 2—2 of Figure 1.

Figure 3 is a view in cross section on different planes denoted by the full line 3—3 of Figure 1.

Figure 4 is a view of one of the valves and in partial section through the cams for operating it.

In the accompanying drawings the numeral 5 indicates a portion of a crank case of an engine, 6 a cylinder secured thereto and rising therefrom, 7 a piston located in the cylinder, and operating upon the driving rod or pitman 8, and 9 a spark plug, all of which parts may be of any ordinary and well known construction, it being understood that the driving rod or pitman will be connected with the crank shaft of the engine in a manner common to devices of this class and also that the engine may consist of such number of cylinders as may be desired.

My invention, in one of its features, comprises a jacket that is constructed in halves divided on a plane passing diametrically through the cylinder and that is applied thereto from opposite sides, these halves being secured together in any suitable manner, as by means of bolts engaging flanges on the halves. The cylinder may be sup-

plied with water chambers 11 in a manner common to engine construction, and the jacket halves contain inlet and exhaust passages 12—13 that will be connected, the former with a source of fuel supply and the latter with an exhaust pipe in a manner that will be readily understood and for which reason such parts are omitted from the showing herein. These jacket halves each contains on its inner face a recess 14 or 15 conforming in shape to the outer surface of the cylinder thereby providing valve chambers between the outer surface of each cylinder and the inner faces of said recesses for inlet and exhaust valves 16—17.

It will be seen, by inspecting Figs. 1 and 2, that the inlet and exhaust valves 16 and 17 respectively, due to their semi-cylindrical shape in cross-section, form a two-part sleeve valve having independently movable parts. Each valve is of a shape in cross section to fit each recess or valve chamber and each valve has valve ports 18—19, the former being located in the lengthwise center of the valve and the ports 19 being located on opposite sides of the center port, and as shown in Figure 4 of the drawings. Each valve is provided with a flat surface on its outside forming a bearing 20 that is adapted to be moved in contact with bearing shafts 21 mounted in ball bearings 22 located at each end of each shaft. In the preferred construction, and as shown herein, two bearing shafts are provided for each valve. Said ball bearings may be of any preferred form and construction, such bearings for the upper shaft being located in a chamber 23 opening from the inner face of a jacket half and such bearings for the lower shaft being located in a chamber 24 opening from the bottom of the jacket half, and as clearly shown in Figure 1 of the drawings. The ball bearings may be retained in place as by caps 25 secured in any suitable manner. A connecting rod 26 extends from each valve to a valve operating cam 27 secured to a cam shaft 28 mounted in any suitable manner in the base of the engine and operatively connected as may be desired with the main shaft of the engine.

In the preferred form of construction and as shown herein, a pair of cams 27 is provided for each valve, each cam having a

valve groove 29 within which roller projections from opposite sides of each connecting rod 26 extend.

Ring packings 30 of any preferred form are located between the inner surface of each valve and the outer surface of the cylinder, and spring pressed packings 31 are located between the inner surfaces of the valve and the outer surface of the cylinder on opposite sides of the ports through the valves, said spring pressed packings being located in recesses 32 preferably formed as to a portion of each recess both in the outer surface of the cylinder and the inner surface of the valve. These spring pressed packings prevent the escape of pressure in a direction circumferentially of the cylinder, and the ring packings, as will be readily understood, prevent the escape of pressure lengthwise of the valve and cylinders.

The connecting rods 26 pass through guides 33 in the division wall between the crank case and the chambers 24 whereby such rods are securely held against any lateral play and a steady movement is imparted thereby to the slide valves. An oil inlet pipe 34 may be employed as a means for supplying oil to the ball bearings. A shim or shims 35 may be inserted between the members of the jacket 10 as a means for adjusting the jacket to the requirements of the valves 16 and to thereby retain the valves against undue looseness. This provides an extremely convenient means for taking up wear with respect to the valves, as it is necessary only to remove a shim or shims for this purpose and the furnishing of new valves is thereby obviated.

40 I claim:—

1. An engine including a cylinder, a multiple section jacket enclosing said cylinder and constructed to be applied thereto from opposite sides for the purpose of varying the space between said cylinder and jacket, said jacket having a port therein, a two-part sleeve valve each part being formed on a circle of the same diameter and located between said jacket and cylinder and having a port registering with the port in said jacket, and means for reciprocating said valve.

2. An engine including a cylinder, a multiple section jacket enclosing said cylinder and constructed to be applied thereto from opposite sides for the purpose of varying the space between said cylinder and jacket, said jacket having inlet and exhaust ports in opposite sections thereof, a two-part sleeve valve each part being formed on a circle of the same diameter and having inlet and exhaust ports and located between the sections of the jacket and the outer surface of the cylinder, and means for reciprocating said valve.

3. An engine including a cylinder, a mul-

70 tiple section jacket having a port therein and a recess formed in the inner surface at the lower part of each section, said jacket enclosing said cylinder and constructed to be applied thereto from opposite sides for the purpose of varying the distance between the inner wall of said jacket and the outer face of said cylinder, a two-part sleeve valve each part being formed on a circle of the same diameter and located between the said jacket and said cylinder and extending into said recess, and means for reciprocating said valves.

4. An engine including a cylinder, a jacket 80 inclosing said cylinder, a multiple part sleeve valve located between the jacket and cylinder and having a flat bearing surface for each part, a bearing shaft adapted to receive the flat bearing surface on said valve, and antifriction bearings for the ends 85 of said shaft and removed from said valve.

5. An engine including a cylinder, a jacket inclosing said cylinder, a multiple part sleeve valve located between the jacket and cylinder and having a flat bearing surface 90 on one side of each part, said jacket being constructed to be applied to the cylinder from opposite sides thereof, a bearing shaft to engage said flat bearing surface on the valve, and antifriction bearings on the opposite ends of said shaft and removed from said valve.

6. An engine including a cylinder, a jacket inclosing said cylinder and constructed to be applied thereto from opposite 100 sides thereof, a multiple part sleeve valve located between said jacket and said cylinder and having a flat bearing surface on one side of each part, said jacket having a recess opening inwardly from the inner side thereof adapted for receiving the flat bearing surface, a bearing shaft to engage said flat surface, and antifriction bearings for said shaft and located in said recess.

7. An engine including a cylinder, a two-part jacket enclosing said cylinder and constructed to be applied thereto from opposite sides thereof, a multiple part sleeve valve located between said jacket and cylinder, a bearing surface projecting from the arc of 115 said sleeve valve formed on each part thereof, said jacket having ports therein and recesses for accommodating said bearing surfaces, a bearing shaft for each bearing surface, and anti-friction bearings for the ends 120 of said shafts that are isolated from said ports.

8. An engine including a cylinder, a multiple section jacket enclosing said cylinder and adapted to be applied thereto from 125 opposite sides thereof for the purpose of varying the space between said cylinder and jacket, a two-part sleeve valve located between said jacket and cylinder, said jacket having a port regis-

tering with a port in said cylinder, circumferentially extending packing rings between said valve and cylinder located above and below said port, longitudinally extending 5 spring pressed packing members between said cylinder and valve located laterally at both sides of said port, and means for operating said valve.

inclosing said cylinder, a valve of curved 10 shape in cross section located between the jacket and cylinder and having a flat bearing surface, a bearing shaft rotating in contact with said flat bearing surface on said valve, and antifriction bearings for the 15 ends of said shaft.

9. An engine including a cylinder, a jacket

KAY FREDRICK ELLEGARD.
